STRANDED WIRE STRUCTURES

Roger W. Stevens, Woodbury, Conn., assignor to United States Steel Corporation, a corporation of New Jersey
Filed May 1, 1964, Ser. No. 364,255
4 Claims. (Cl. 57—145)

This invention relates to stranded wire structures and more particularly to stranded wire structure for use as hoisting ropes. Such ropes are subjected to abrasion and abuse and yet must be flexible to enable them to pass around sheaves and drums. Such ropes are also subject to short peak loads which may break the rope, especially if the rope does not stretch or elongate readily under the peak load.

It is therefore an object of my invention to provide a stranded wire structure which has a flexible interior and large exterior wires to make it abrasive and abuse resistant.

Another object is to provide such a stranded wire structure which will elongate under peak loads.

These and other objects will be more apparent after referring to the following specification and attached drawing, in which:

FIGURE 1 is an end view of a wire rope constructed according to my invention; and

FIGURE 2 is a view, similar to FIGURE 1, showing a second embodiment of my invention.

Referring more particularly to FIGURE 1 of the drawings, reference numeral 2 indicates an independent wire rope core which is surrounded by six strands 4. The independent wire rope core consists of a six wire center strand 6 having six strands 8 of six wires each stranded around the center strand 6. Other constructions of independent wire rope cores, such as 7 x 7 may also be used. Each of the strands 4 consists of a center wire 10 with four wires 12 of equal diameter stranded around the wire 10. Four wires 14 of one diameter and four wires 16 of a second diameter smaller than the diameter of wires 14 are stranded around the wires 12 with the smaller diameter wires arranged alternately with the larger diameter wires. Eight wires 18 of equal diameter are stranded around the wires 14 and 16.

In one particular embodiment, the core strand of the independent wire rope core is made of a center wire having a diameter of .040 in. surrounded by five wires having a diameter of .048 in. and the outer strands each have a center wire having a diameter of .033 in. surrounded by five wires having a diameter of .040 in. The diameter of the independent wire rope core is .360 in. In this embodiment the wires of the strand 4, like the wires of the core 2, are made of steel with the diameter of wire 10 being .016 in., the diameter of wires 12 being .035 in.,

2

the diameter of wires 14 being .048 in., the diameter of wires 16 being .039 in. and the diameter of wires 18 being .074 in.

The wire rope of FIGURE 2 differs from that of FIGURE 1 only by the substitution of a fiber core 20 for the independent wire rope core 2.

In each of the embodiments the rope may be regular lay, Lang lay or alternate lay.

While the two embodiments of my invention have been shown and described, it will be apparent that other adaptations and modifications may be made without departing from the scope of the following claims.

I claim:

1. A stranded wire structure comprising a center wire, 15 four wires of equal diameter stranded around said center wire, eight wires stranded around four wires, four of said eight wires being of equal diameter and the other four of said eight wires being of an equal diameter smaller than the diameter of the first mentioned four wires of said eight wires, the smaller diameter wires being arranged alternately with the larger diameter wires, and eight wires of equal diameter stranded around said first named eight wires.

2. A stranded wire structure comprising a center core, 25 and six strands stranded around said center core, each of said strands including a center wire, four wires of equal diameter stranded around said center wire, eight wires stranded around said four wires, four of said eight wires being of equal diameter and the other four of said eight wires being of an equal diameter smaller than the diameter of the first mentioned four wires of said eight wires, the smaller diameter wires being arranged alternately with the larger diameter wires, and eight wires of equal diameter stranded around said first named eight wires.

3. A stranded wire structure according to claim 2 in which said center core is a stranded wire structure comprising a six wire center strand, and six strands of six wires each stranded around said center strand.

4. A stranded wire structure according to claim 2 in which said center core is fiber.
